MIXING AND DISPENSING FAUCET

Herman H. Harr, Newark, N. J.

Application October 19, 1944, Serial No. 559,344

6 Claims. (Cl. 225—26)

1

This invention relates to a novel construction of means for dispensing a beverage; and the invention has reference, more particularly, to means adapted to mix and dispense a beverage comprising liquid ingredients simultaneously drawn from independent supply sources.

The invention has for an object to provide a novel means for mixing and dispensing a beverage formed by a plurality of liquid ingredients, said means comprising a faucet having a plurality of liquid intake means adapted to be respectively connected to independent sources of different liquid ingredients which, when mixed together, produce a beverage; said faucet having manipulatable control valve means common to said liquid intake means; the form and arrangement of the common control valve means relative to the faucet chamber and its discharge spout being such that the plurality of liquids are simultaneously drawn from their respective supply sources, are intermingled within the faucet chamber, and the resultant beverage composed thereof thereupon discharged through the faucet spout.

Another object of the invention is to provide a faucet for dispensing a mixture of two liquid components, one of which is gas-charged or under pressure, such, e. g., as carbonated water, and the other of which is a flavoring liquid or syrup required to be supplied in minor volume relative to a major volume of the first mentioned liquid, wherein the relation of the intake of the pressure liquid to that of the flavoring liquid, and the form and relation of the common intake control valve means to the faucet chamber and faucet discharge spout is such that the out-flow of the pressure liquid is utilized to facilitate induction and controlled simultaneous out-flow of flavoring liquid, thus avoiding necessity for prior bulk measurement of the latter liquid.

Another object of the invention is to provide a faucet adapted to mix and dispense two liquids, one of which is gas-charged or under pressure, wherein means is provided for reducing and controlling the pressure of the latter liquid prior to flow thereof into the faucet chamber, whereby the in-flow thereof is rendered sufficiently uniform to prevent abrupt or excessive changes in velocity, and whereby this liquid is kept in substantially calm liquid condition with its activating gases retained therein, and so that the ultimately formed beverage, containing the added flavoring liquid, may be dispensed from the faucet spout and into a glass without undue gas releasing agitation, spouting and splashing.

The invention has for a further object to pro-

2

vide a means for mixing and dispensing a beverage comprising liquids received by a faucet from independent or different sources, said faucet having separate intakes for each liquid, auxiliary valve means being provided for modifying the inflow volume of at least one of said liquids.

Other objects of the invention, not at this time more particularly enumerated, will be understood from the following detailed description of the

10 same.

An illustrative embodiment of this invention is shown in the accompanying drawings, in which—

Fig. 1 is a vertical longitudinal sectional view through a mixing and dispensing faucet according to this invention, showing the same in closed condition; Fig. 2 is a fragmentary view thereof in part vertical longitudinal section and in part elevation, showing the same in open condition; and Fig. 3 is a fragmentary transverse vertical sectional view, taken on line 3—3 in Fig. 2.

20 Similar characters of reference are employed in the above described views, to indicate corresponding parts.

The illustrative embodiment of this invention 25 as shown in the drawings includes a faucet body 5 having an internal chamber 6 from which leads a discharge spout 7 with which the faucet body is provided. In its inner end portion, said faucet body 5 is provided with an enlarged valve chamber 30 8 which communicates with the faucet chamber 6, said valve chamber being provided with a valve seat 9 at the juncture thereof with said faucet chamber 6; said valve chamber 8 providing the faucet intake for one liquid desired to be delivered into the faucet. In its outer end portion, said faucet body 5 is provided with an outwardly closed slideway 10 which is inwardly open toward the faucet chamber 6. Mounted to slidably reciprocate in said slideway 10 is a valve 35 piece 11, the inner end portion of which extends into the faucet chamber 6. Extending axially from the inner end of said valve piece 11 and into the valve chamber 8 is a stem 12 of reduced diameter, to the free end portion of which is suitably affixed a valve head 13 for cooperation with the valve seat 9. Provided in the wall of the faucet body 5 is an intake port 14 which constitutes the faucet intake for a second liquid desired to be delivered into the faucet. Provided in 40 the valve piece 11 is a diametrically disposed valve port 15 for cooperation with said intake port 14.

The valve piece 11, with its described associated parts, is adapted to be axially reciprocated by an external hand lever 16 which is pivot-

ally mounted by suitable means on and in connection with the outer end portion of the faucet body. Said hand lever is provided at its inner end with an inner lever arm 17 which engages in a slot 18 with which the outer end portion of the valve piece 11 is provided, whereby movements of the hand lever produce operative movements of the valve piece and its associated parts.

Additionally provided in the wall of the faucet body 5 is an air inlet passage 19, and provided in the valve piece 11 is a diametrically disposed vacuum breaker port 20 which cooperates with said air inlet passage.

The underside of the inner end portion of the valve piece 11 is transversely cut away to provide a substantially flat wall surface 21 which terminates in an inclined end portion 22 which merges with the underside contour of the valve piece. The passage of the faucet spout 7 inclines downwardly and outwardly from its point of communication with the faucet chamber 6, and consequently the internal surface of the spout bottom wall diverges from the flat wall surface 21 of the valve piece 11, whereby a Venturi-like intermediate passage 23 is formed between the valve chamber 8 and the spout passage outlet, said Venturi-like passage being disposed to underlie the valve port 15 when the latter is moved to opened alignment with the second liquid intake port 14. The purpose and advantage of said Venturi-like passage will be hereinafter more fully explained.

When the valve piece 11 is retracted to normal closed position (see Fig. 1), to which position it is moved by inward swinging of the hand lever 16, the valve head 13 seats against the valve seat 9, thus closing the intake of one liquid, while at the same time the valve port 15 is withdrawn out of alignment with the intake port 14 so that the valve piece 11 also closes the intake of the second liquid. When the valve piece 11 is thus positioned to close the liquid intakes, its vacuum breaker port 20 is disposed in alignment with the air inlet passage 19, thereby opening the interior of the faucet chamber to communication with the atmosphere, whereby to assure prompt and complete evacuation of liquid from the faucet chamber and spout, and thus avoiding tendency of prolonged dripping of liquid from the spout.

When the valve piece 11 is advanced to open position (see Fig. 2), to which position it is moved by outward swinging of the hand lever 16, the valve head 13 is removed from the valve seat 9, thus opening the intake of one liquid, while at the same time the valve port 15 is advanced to aligned relation to the intake port 14, thus opening the intake of the second liquid. When thus advanced, the valve piece 11 carries its vacuum breaker port 20 out of alignment with the air inlet passage 19 so that the valve piece 11 closes the latter when the faucet is open to the flow of the liquids therethrough.

Connected with the inner end of the faucet body 5, in axially aligned relation thereto, is an exteriorly screw-threaded shank 24 adapted to be inserted through and suitably affixed to the wall 25 of a cabinet or other support for the faucet. Said shank 24 and faucet body 5 are joined together as a unitary assembly by suitable coupling union means 26, and the joint formed by their meeting ends is sealed by an interposed gasket 27. Provided in the faucet opposed end of said shank 24 is a chamber 28 which forms an extension of the valve chamber 8 of the faucet body 5. Extending axially through the shank 24

is a liquid delivery passage 29 leading to said chamber 28. In use, the liquid delivery passage 29 of said shank 24 is coupled to a liquid supply line (not shown), which leads from the source of supply of the liquid, admission of which to the faucet chamber 6 is controlled by the valve head 13 of the faucet valve piece 11. When this liquid is gas-charged or under pressure, the diameter of the delivery passage 29 is sufficiently limited in size to effect reduction of pressure of the liquid and to maintain a substantially uniform small volume of flow per unit of length, whereby to prevent agitation and sudden expansion of the liquid. As a further aid in reducing the pressure of the gas-charged or pressure liquid admitted to the faucet, while at the same time deflecting the entering liquid for passage around the open valve head 13, whereby to prevent head-on collision of the delivered liquid stream with the latter, and thus to avoid undue turbulence of the liquid and consequent premature release of any activating gases contained therein, additional combined pressure reducing and deflector means is arranged within the chamber 28, and connected in communication with the discharge end of the shank passage 29. This means, in one illustrative form thereof as shown, comprises a liquid discharge nozzle 30 of smaller diameter than that of the chamber 28, the same having at its inner end an axially extending screw-threaded stem 31 adapted to be screwed into the body of the shank 24. Entering the nozzle 30 through said stem 31 is a passage 32 which is aligned with the shank passage 29 for communication therewith, and extending radially from the inner end of said passage 32 are a plurality of lateral discharge passages 33 opening out from the periphery of the nozzle 30. When the nozzle is affixed to the shank 24, its inner end abuts the bottom of the chamber 28, and the periphery of the nozzle is spaced concentrically to the sides of said chamber 28, thus forming an annular passage 34 through which the emitted liquid flows in such manner as to be deflected for passage around the valve head 13, thus preventing undue agitation and turbulence of the liquid, so that in-flow of the liquid into the faucet chamber 6 is uniformly maintained without abrupt or excessive changes of velocity, and so that substantially calm condition of the liquid is assured, and premature release of any contained activating gases is avoided. As a consequence of this, flow of the gas charged or pressure liquid through the faucet, and its mixture with added flavoring liquid is so controlled that the ultimate beverage provided by the mixture will discharge smoothly and quietly from the faucet spout and into a glass without undue gas releasing agitation, spouting or splashing.

Suitably coupled with the faucet body 5, for communication with the intake port 14 thereof, is a second liquid delivery conduit 35, which leads from a source of second liquid supply, such, e. g., as a supply of flavoring liquid or syrup. Provided in the line of said conduit 35, and preferably positioned closely adjacent to the intake port 14 with which the latter is coupled, is a manipulatable regulating valve 36, by means of which the flow delivery of the second liquid to the faucet chamber 6 may be suitably modified according to a selected proportional ratio of volume of the second liquid desired to be mixed with a given volume of the first liquid admitted to the faucet chamber when the faucet is opened. This valve 36 may be of any desired known type, and, e. g.,

may be of the well-known plug type which, by rotative adjustment of its valve plug, may delimit the area of the conduit passage selectively between full open and closed positions of the valve plug.

Where the faucet is utilized to serve a beverage comprising a gas-charged or pressure liquid, such, e. g., as carbonated water, and an inert or flavoring liquid, when the faucet is opened the former liquid is delivered through the shank passage 29 and nozzle 30 to flow past the unseated valve head 13 into the faucet chamber 6, and thence through the Venturi-like passage 23 beneath the valve piece 11, while the latter liquid is admitted to said Venturi-like passage 23 through the aligned intake port 14 and valve port 15. As the pressure liquid flows through the Venturi-like passage 23, its velocity is somewhat increased at the point of restriction, and as a consequence a suction effect is exerted at the outlet end of the valve port 15 which aids induction or emission of the flavoring liquid therefrom, so that a given volume of the latter is drawn and mingles with the outgoing stream of the pressure liquid. The volume of the flavoring liquid may be proportionally predetermined relative to the volume of pressure liquid by adjusting the regulating valve 36, taking into consideration the degree of pressure to which the pressure liquid is subject. In this way, a desirably proportioned mixture of the two liquids may be formed within and thereupon dispensed from the faucet.

While the faucet is well adapted to mix and dispense two liquids one of which is a gas-charged or pressure liquid, it may also be advantageously utilized to mix and dispense two liquids which are both inert. In the latter case, one liquid may be delivered to the faucet chamber through the shank passage and intake controlled by the valve head 13, in which case the diameter of the shank passage may be suitably sized and the nozzle 30 omitted, so that flow of said liquid in desired volume under head pressure or otherwise impressed pressure may be attained. The other liquid is delivered through the aligned intake port 14 and valve port 15, and its flow in desired volume under head pressure or otherwise impressed pressure may be controlled by adjusting the regulating valve 36.

Having now described my invention, I claim:

1. A faucet for mixing and dispensing a beverage formed by a plurality of liquid ingredients, one of which is under pressure, comprising a faucet body having a longitudinal chamber terminating at its inner end in a valve chamber defining a valve seat, said faucet body having a spout leading from said faucet chamber the passage of which is obliquely divergent to the longitudinal axis of said faucet chamber, a longitudinal valve piece slidably movable in said faucet chamber and having a valve head connected with its inner end to cooperate with said valve seat for control of admission of the pressure liquid longitudinally into said faucet chamber, said faucet body having a side entering intake port, said valve piece having a transverse valve port cooperative with said intake port for simultaneous admission of another liquid when said valve piece and valve head are moved to admit said pressure liquid, means to actuate said valve piece to thus simultaneously control flow of both liquids, and said valve-piece having an inclined underside adapted when said valve piece is in liquid admitting position to cooperate with the inner portion of the divergent spout passage so

as to provide a Venturi-like passage through which the pressure liquid passes and into which the second liquid is laterally discharged.

5 2. A faucet as defined in claim 1, including a shank extending from the inner end of said faucet body having an axial passage through which the pressure liquid is served to the faucet chamber, a pressure reducing and liquid deflecting means connected with the discharge end of said shank passage to lie within the valve chamber and outwardly of the valve head therein.

10 3. A faucet as defined in claim 1, including a conduit coupled in communication with the side entering intake port through which the second liquid is served to the faucet chamber, and a regulating valve means in the line of said conduit.

15 4. A faucet as defined in claim 1, including a shank extending from the inner end of said faucet body having an axial passage through which the pressure liquid is served to the faucet chamber, a pressure reducing and liquid deflecting means connected with the discharge end of said shank passage to lie within the valve chamber and outwardly of the valve head therein, a conduit coupled in communication with the side entering intake port through which the second liquid is served to the faucet chamber, and a regulating valve in the line of said conduit.

20 5. A faucet as defined in claim 1, including a shank extending from the inner end of said faucet body, the faucet opposed end of said shank having a chamber opposed to and forming an extension of the terminal valve chamber of the faucet body, said shank having a longitudinal passage through which the pressure liquid is served to the faucet, a nozzle affixed to said shank and disposed within the shank chamber in substantially concentrically spaced relation to the side walls of the latter to provide an intermediate liquid discharge passage, and said nozzle having an outwardly closed axial passage communicating with said shank passage and radial passage means extending between said axial passage and said liquid discharge passage.

25 6. A faucet as defined in claim 1, including a shank extending from the inner end of said faucet body, the faucet opposed end of said shank having a chamber opposed to and forming an extension of the terminal valve chamber of the faucet body, said shank having a longitudinal passage through which the pressure liquid is served to the faucet, a nozzle affixed to said shank and disposed within the shank chamber in substantially concentrically spaced relation to the side walls of the latter to provide an intermediate liquid discharge passage, said nozzle having an outwardly closed axial passage communicating with said shank passage and radial passage means extending between said axial passage and said liquid discharge passage, a conduit coupled in communication with the side entering intake port through which the second liquid is served to the faucet, and a regulating valve in the line of said conduit.
